UNITED STATES PATENT OFFICE.

AUGUST THOMSEN, OF GLENDALE, NEW YORK.

MACHINE FOR MAKING METAL SPOUTS AND TUBES.

1,402,913.

Specification of Letters Patent. Patented Jan. 10, 1922.

Application filed July 16, 1920. Serial No. 396,634.

To all whom it may concern:

Be it known that I, AUGUST THOMSEN, a citizen of the United States, and a resident of the borough of Queens, Glendale, Long Island, in the county of Queens and State of New York, (whose post-office address is 234 Edison Place, Glendale, Long Island,) have invented new and useful Improvements in Machines for Making Metal Spouts and 10 Tubes, of which the following is a full, clear, and exact description.

The present invention relates particularly to machinery for manufacturing the end pieces or shapers for spouts. These spouts 15 may have various uses. One particular use is in conjunction with a decorating gun for confectioners' use, by which ornamentation is placed upon cakes or similar articles. Other spouts, such as required for oil cans 20 and similar devices, are also formed by this machine.

Among the principal objects which the present invention has in view are: To impart more perfect shape than heretofore to 25 the spout-forming members; to simplify the construction of the spout; to diminish the time required for the construction; to increase the scope of usefulness in machines of the character mentioned; and to permit 30 rapid and simple alteration in the shapes of the spouts formed thereby.

Drawings.

Figure 1 is a top plan view of a machine 35 constructed and arranged in accordance with the present invention.

Figure 2 is a side view of the same, the machine being shown in its inactive or normal position.

40 Figure 3 is a similar view showing the parts in the initial step of the operation, portions of the machine being cut away to disclose the interior construction thereof.

Figure 4 is a cross section, the section 45 being taken as on the line 4—4 in Figure 1.

Figure 5 is a cross section, the section being taken as on the line 5—5, the shaping jaws being disposed in the active position thereof, and that assumed at the completion 50 of the tube-folding operation.

Figure 6 is an end view of the machine showing the inactive position of said jaws and of the parts associated therewith.

Figure 7 is a side view of a machine of 55 the character mentioned, constructed and

arranged in accordance with a modified form of the invention, parts of the construction being cut away to disclose the interior construction, parts being shown in section for the same purpose. 60

Figure 8 is a detail view showing in plan the means employed for actively disposing the centering member with which the machine is provided.

Figure 9 is a detail view showing a perspective of one of the spouts constructed by the herein-disclosed machine. 65

Figure 10 is a detail view showing the metal blank of which the said spout is formed.

Description.

As seen in the drawings, and particularly by reference to Figures 10 and 9 thereof, the blank A shown in the former figure is curled about a shaping mandrel 15 to be 75 manually stripped therefrom as the spout B disclosed in the latter of the said figures. The shaping or curling of the blank to the shape shown in Figure 9 is primarily accomplished by the smoothing blades 16 80 which are adjustably secured by set screws 17 on sliding plates 18. As shown best in Figure 4 of the drawings, there are two plates 18, which plates are guided in slots provided in the swinging frames 19. There 85 are two frames 19, each being independently pivotally mounted on the shank 20 of the mandrel 15 and on the end of a lay mandrel 21. The mandrels 15 and 21 are held stationarily in heads 22 at the upper ends of 90 standards 23. The standards 23 are made secure to the base plate 24.

The plates 18 are further guided by the braces 25 and by the shank of a bolt 26 which extends through the said braces and 95 through perpendicular slots provided in said plates. These bolts 26 assist in preventing the plates 18 shifting lengthwise of the frames 19.

The plates 18 are reciprocated to and from 100 the mandrel 15 by means of levers 27, of which there are two, each being furnished with a handle 28. The levers 27 are of the character generally termed bell-crank levers, and the short arm 29 thereof is attached by 105 means of a pivot screw 30 to one of the plates 18. To permit the movement of the screw 30 through outer brace 25 a curved slot 31 is provided in the said brace.

The smoothing blades 16 are adjustable 110

on the plates 18, each of the smoothing blades being provided with an elongated slot 32 through which the shanks of the screws 17 extend.

5 As seen best in Figure 4 of the drawings, the screw 17 extends beyond the plate 18 to form in conjunction with the braces 25 a stop for determining the retracted position of the plates 18. This position is shown best 10 in Figure 2 of the drawings, where the head of the screw 17 is disclosed as bottomed in a recess 33 in the brace 25.

The blanks shown in Figure 10 of the drawings are disposed under the mandrel 15 and 15 above the blades 16, the blades 16 being retracted to leave a clearway below the said mandrel, as seen best in Figure 2 of the drawings.

The position of the flat metal is regulated 20 by the gages 34. The gages 34 are movably attached to extended brackets 35. The brackets 35 are each provided with a lengthwise slot 36 through which the shank of fastening bolts 37 extend. These bolts are 25 employed for determining the position of the gages 34.

As seen best in Figure 1 of the drawings, the gages 34 are rectangular in shape, the hollow angles being turned toward each 30 other to receive the lateral corners of the blank shown in Figure 10.

With the mechanism constructed and arranged as above disclosed, the operation of curling the blank shown in Figure 10 to 35 form the spout shown in Figure 9 is as follows: The blanks are successively fed to the mechanism by placing the blanks within the gages 34, to rest on the support 38 in the said gages. The operator then grasps the 40 handles 28 and moves them from the position shown in Figures 1 and 2 of the drawings to the position shown in Figure 3. This closes the blades 16 on the blank to hold the same between the said blades and the said 45 mandrel at opposite sides of the said mandrel. The handles are then swung from the position shown in Figure 4 to the position shown in Figure 5. The levers 27, of which the handles 28 form a part, and the 50 parts associated therewith including the blades 16, are swung around the axes of the mandrels 15 and 21, with the result that the metal blank shown in Figure 10 is curled to the form shown in Figure 9, closely hugging the mandrel 15. In the final operation, 55 the lapped seam shown in Figure 9 is accomplished by rocking both levers and parts associated therewith around the mandrel 15 and partially formed spout thereon in the 60 direction in which the outer layer of the seam is folded.

Having thus shaped the blank into the spout, the handles 28 and parts associated therewith are returned to the original position disclosed in Figures 1 and 2 of the

drawings, when a succeeding blank is placed within the gages 34 and the operation repeated.

It is obvious that the operation performed by means of this mechanism is very rapid. 70 It is also obvious that the shape imparted to the spouts by means of the mechanism is accurate, with the result that a perfect product is insured.

Each of the spouts is removed by hand 75 or stripped from the mandrel 15 after the blades 16 have been lowered.

The spouts formed by the present machine vary in length and diameter, as shown by a contrast of the spout C indicated in 80 Figures 7 and 8 with the spout B shown in Figures 3 and 9. When making the spout C it is obvious that room must be provided in line with the mandrel 15 and in front 85 thereof for the removal of the said spout. This is accomplished by providing the lay mandrel 39, which is slidably held in the head 22. To secure the mandrel 39 in the head 22 the said head has an extended flange 90 40 wherein bayonet slots 41 are provided to engage pins 42 extended from the mandrel 39. To facilitate the operation of the mandrel 39, handle bars 43 are provided whereby the said mandrel may be quickly 95 adjusted to service position. To assist the elongated mandrel 15 and to steady the same during the operation, the mandrel 39 has a centering pin 44 the end of which enters a shallow socket in the said mandrel 15 or within the pocket formed by the contracted end of the spout C. In either event, 100 the free end of the mandrel 15 and spout being formed thereon are supported and steadied during the operation of curling the blank.

While the mechanism has been shown and described as forming tapered spouts, it will be understood that when desired cylindrical tubes may also be constructed by the mechanism by substituting for the tapered mandrels 15 the other cylindrical mandrels. 110 When forming the tubes referred to they usually are of such a length as to require the opening in the head 22 and the removable mandrel 39 so that they may be stripped from the mandrel and removed from the mechanism by way of the passage through the said head 22.

Claims.

1. A machine as characterized, comprising a shaping mandrel; a plurality of swinging frames pivotally mounted to swing concentric to said mandrel; smoothing blades reciprocatively mounted in said frames; manually operated means for moving said blades to and from said mandrel; and a plurality of gage members for determining the position of the blanks fed to said machine for manipulation thereby.

2. A machine as characterized, comprising a shaping mandrel; a plurality of swinging frames pivotally mounted to swing concentric to said mandrel; smoothing blades reciprocatively mounted in said frames; manually operated means for moving said blades to and from said mandrel; and a plurality of gage members for determining the position of the blanks fed to said machine for manipulation thereby, said members embodying a plurality of angularly shaped members supported by said frames. 40

10 3. A machine as characterized, comprising a shaping mandrel, a plurality of swinging frames pivotally mounted to swing concentric to said mandrel; smoothing blades reciprocatively mounted in said frames; manually operated means for moving said blades to and from said mandrel; a plurality of gage members for determining the position of the blanks fed to said machine for manipulation thereby, said members embodying a plurality of angularly shaped members supported by said frames; and means for adjusting said angular members toward and away from the exposed end of said mandrel. 45

15 20 25 30 35 40 45 50 55 60 65 70 75 80 85 90 95 100

4. A machine as characterized, comprising a shaping mandrel; a plurality of swinging frames pivotally mounted to swing concentric to said mandrel; smoothing blades reciprocatively mounted in said frames; manually operated means for moving said blades to and from said mandrel; a plurality of gage members for determining the position of the blanks fed to said machine for manipulation thereby, said members embodying a plurality of angularly shaped members supported by said frames; and means for adjusting said angular members toward and away from the exposed end of said mandrel. 40

5. A machine as characterized, comprising a shaping mandrel; a plurality of swinging frames pivotally mounted to swing about said mandrel concentric thereto; a plurality of reciprocating plates one mounted in each of said frames; a plurality of manually operated levers for moving said plates to and from said mandrel; a plurality of smoothing blades detachably attached to each of said plates; and means for adjusting said blades on said plates to conform to the surface of said mandrel. 50

6. A machine as characterized, comprising a shaping mandrel; a plurality of shaping frames pivotally mounted concentric to said mandrel to swing about the same; a steady rest for the free end of said mandrel, said steady rest being removable to form a passageway for the article formed on said mandrel when stripped therefrom lengthwise thereof. 60

65 70 75 80 85 90 95 100

AUGUST THOMSEN.
